UNITED STATES PATENT OFFICE.

FRANKLIN PIERCE MCSELFRESH, OF JACKSON TOWNSHIP, SHELBY COUNTY, IOWA.

HERNIAL TRUSS.

SPECIFICATION forming part of Letters Patent No. 746,872, dated December 15, 1903.

Application filed March 24, 1903. Serial No. 149,385. (No model.)

To all whom it may concern.

Be it known that I, FRANKLIN PIERCE MCSELFRESH, a citizen of the United States, residing in Jackson township, in the county of 5 Shelby and State of Iowa, have invented a new and useful Truss, of which the following is a specification.

This invention relates to certain improvements in trusses, and has for its object to provide a simple, inexpensive, and efficient device of this character capable of use either as a single or double truss, which may be easily and readily adjusted without unnecessary pressure to suit all forms of hernia, and which 15 from its simplicity gives entire freedom of movement and comfort to the wearer without danger of displacement.

A further object of the invention is to provide a truss which may be readily changed 20 from a right to a left hand truss, in which the pressure exerted on the parts affected is obtained from the inherent spring tendency of the pad-supporting arms, thereby obviating the use of elastic or similar supporting-belts, 25 which clamp the body tightly and impede the circulation of the blood, which permits the body to be bent in any position without the liability of the pads chafing or otherwise injuring the affected parts, and in which the pads 30 may be raised or lowered or adjusted at any angle or inclination with respect to the body.

The invention consists in the construction and novel combination and arrangement of parts hereinafter fully described, illustrated 35 in the accompanying drawings, and pointed out in the claims hereto appended, it being understood that various changes in form, proportion, and minor details of construction may be resorted to without departing from 40 the spirit or sacrificing any of the advantages of this invention.

In the accompanying drawings, Figure 1 is a perspective view of a truss constructed in accordance with my invention. Fig. 2 is a 45 vertical sectional view of the same. Fig. 3 is a side elevation of one of the pads and supporting-arms, showing in dotted lines the bracket in the elevated position; and Fig. 4 is a detail perspective view of the pad-supporting arms.

Similar numerals of reference indicate cor-

responding parts in all the figures of the drawings.

1 designates a supporting-belt, which may be formed of canvas, leather, or other suitable non-elastic material, having a piece of pliable or malleable wire 2 bent into the form of a loop secured to the front thereof, the top and bottom of the loop lying parallel with the edges of the belt and being held in position by retaining-strips 3, stitched or otherwise secured to the belt, as shown. Pivotally secured to the top of the loop 2 at points intermediate its length is a pair of adjustable brackets 4, the opposite ends of which are 55 bent to form eyes or loops which encircle the wire and permit said brackets to turn freely thereon. The brackets 4 are each provided with longitudinally-extending pins or lugs 5, adapted to receive eyes 6, formed in the ends 60 of spring pad-supporting arms 7, which loosely embrace said lugs and permit the removal of the arms 7 when desired, as will be more fully explained hereinafter. Each pad-supporting arm 7 is preferably formed of a single piece of 70 spring-wire bent on itself to form a number of flat loops 8, the opposite ends thereof extending upwardly, forming a pair of slightly-divergent arms, terminating in the eyes 6. Slidably secured in any suitable manner to the bottom 75 of the loop 2 and in vertical alinement with the brackets 4 are clamping guides or loops 9, adapted to receive the pad-supporting arms 7, which pass through said loop or guide. The pad 10, which may be of any desired 80 shape, is preferably oval, as shown, and consists of a body portion provided with a packing 11, of felt or similar elastic material, and a face-plate 12, having secured thereto a leather disk 13. Interposed between the 85 packing 11 and the disk 13 are the flat loops 8, the opposite faces of which are serrated or roughened, as shown, and the pad is secured in position by means of a clamping-screw 14, which passes through the face-plate and one 90 of said loops, engaging the body of said pad. The supporting-belt is provided with the usual under straps 15, the free ends of which are provided with T-shaped heads adapted to fit within sockets 16 in the face-plate 12. 95

In fastening the pads to the belt the spring-supporting arms are passed through the

guides 9 by turning the pad sidewise and pressing the arms inwardly until the eyes lie flat against the belt, when the arms may be introduced therein, after which the arms are forced upwardly and the ends thereof pressed outwardly and passed over the lugs on the supporting-bracket 4, the bracket and supporting-arms being locked to the loop by pulling the arms downwardly through the clamping-guide. The pad may now be adjusted vertically by loosening the set-screw and sliding said pad upwardly, or the pad may be turned in the arc of a circle at any desired angle with respect to the belt, using the set-screw as a pivot. The pressure of the pad may be regulated by bending the wire composing the spring-supporting arms inwardly or outwardly, as the case may be, and said pad may be adjusted independently of the set-screw by forcing the pad upwardly, which causes the pivoted bracket to swing upwardly on the wire or loop 2, thereby elevating the pad. The pliable wire in the belt permits said belt being bent to conform to the shape of the body, in which position it will be loosely supported by reason of the pressure exerted on the body by the supporting-arms, allowing the body to move within the belt when bending or stooping, while the pads remain relatively fixed, thereby preventing rubbing or chafing of the affected parts. When it is desired to remove the pads for any reason, the pad and supporting-arms are forced upwardly, causing the bracket to assume the position shown in dotted lines in Fig. 1 of the drawings. The arms may then be disengaged from the pins or lugs and the pad removed by drawing downwardly on the same and giving the arms a slight turn, permitting said arms to clear the guide or loop.

It will be observed that when the brackets are thrown upwardly the relative distance between said bracket and the clamping-guide is materially increased, thereby permitting the supporting-arms to be easily swung outwardly from engagement with the lugs or pins, and when said brackets are swung downwardly to their full extent the distance being lessened the divergent arms will be drawn downwardly through the guide, securely clamping said arms and locking the pad in position.

The brackets and guides are free to slide on the loop lengthwise of the belt, and the pads are adjustable on the supporting-arms both angularly and vertically.

From the foregoing description it will be seen that I have provided an exceedingly simple and efficient truss, the pads of which may be easily removed or interchanged and adjusted to suit various forms of hernia, the truss being so constructed that the spring-supporting arms not only give the desired pressure to the pad, but also support the belt in position on the wearer without the use of wire supports, elastic belts, and similar

devices which impede the circulation of the body.

Having thus described the invention, what I claim, and desire to secure by Letters Patent, is—

1. A truss comprising a belt, a support forming part of the belt, a bracket pivoted to the support and longitudinally adjustable thereon, and a pad provided with divergent spring-supporting arms detachably secured to the bracket. 75

2. A truss comprising a belt, a pliable loop secured to the belt, a bracket pivoted to the loop and longitudinally adjustable thereon, and a pad-carrying arm detachably secured to the bracket. 80

3. A truss comprising a belt, a support forming part of the belt, a bracket pivoted to the support and longitudinally adjustable thereon, a guide carried by the support and a pad provided with spring-supporting arms passing through the guide and engaging the bracket. 85

4. A truss comprising a belt, a pliable loop secured to the belt, a bracket pivoted to the loop and a pad provided with spring-supporting arms adapted to engage the bracket. 90

5. A truss comprising a belt, a pliable metal loop secured to the belt, a bracket pivoted to the upper portion of the loop, a guide secured to the lower portion of said loop, and a pad provided with spring-supporting arms adapted to engage the bracket. 95

6. A truss comprising a non-elastic belt, a reinforcing pliable loop secured to the belt, a bracket pivoted to the upper portion of the loop, a guide carried by the lower end thereof, and an adjustable pad provided with upwardly-extending spring-arms passing through the guide and engaging the bracket. 100 105

7. A truss comprising a belt, a reinforcing pliable loop secured thereto, a bracket provided with laterally-extending pins or lugs pivoted to the upper portion of the loop, a guide secured to the lower portion thereof, a sectional pad, and a pair of spring-supporting arms adjustably secured to the pad, and provided with terminal eyes or loops adapted to engage the pins or the bracket. 110

8. A truss comprising a belt, a pliable loop secured to the belt, a bracket pivoted to the loop, a sectional pad, spring-supporting arms provided with terminal eyes adapted to engage the bracket and having lower end portions bent to form a plurality of flat loops 115 120 adjustably secured to the pad, and means for clamping the pad to the arms.

9. A truss comprising a belt, a pliable loop secured to the belt, a bracket pivoted to the upper portion of the loop, a guide slidably mounted on the lower end thereof and an adjustable pad provided with upwardly-extending divergent spring-arms passing through the guide and engaging the bracket. 125

10. In a truss, a belt, a loop forming a part 130 of the belt, a bracket adjustable lengthwise of the upper portion of the loop, a guide ad-

justable lengthwise of the lower portion of the loop, a pad - carrying arm extending through the guide and having terminal arms detachably secured to the bracket, and a pad secured to said arm.

5 11. In a device of the class specified, a belt, a pad, and a pad-carrying arm comprising a section of wire linked to form a plurality of substantially parallel loops having serrated

surfaces, and a pad-clamping means for holding the pad to said arm.

In testimony that I claim the foregoing as my own I have hereto affixed my signature in the presence of two witnesses.

FRANKLIN PIERCE McELFRESH.
